CLAIM

The ornamental design for a chipping hammer adapter handle, as shown and described.

DESCRIPTION

FIG. 1 is a front view of a chipping hammer adapter handle; FIG. 2 is a top view thereof;

FIG. 3 is a right side view thereof;

FIG. 4 is a left side view thereof;

FIG. 5 is a bottom view thereof;

FIG. 6 is a rear view thereof; and,

FIG. 7 is an isometric view thereof.

The broken lines depict portions of the article and environment that form no part of the claimed design.
